US00D778061S

(12) **United States Design Patent**
Fretwell et al.

(10) **Patent No.:** **US D778,061 S**
(45) **Date of Patent:** **** Feb. 7, 2017**

(54) **TOOTHBRUSH**

(71) Applicant: **GOSMILE, INC.**, Berkeley, CA (US)

(72) Inventors: **Allison Fretwell**, San Francisco, CA (US); **Lou Lentine**, Chattanooga, TN (US)

(73) Assignee: **GOSMILE, LLC.**, Austin, TX (US)

(**) Term: **15 Years**

(21) Appl. No.: **29/531,104**

(22) Filed: **Jun. 23, 2015**

(51) **LOC (10) Cl. 04-02**

(52) **U.S. Cl.**

USPC **D4/108**

(57) **CLAIM**

The ornamental design for a toothbrush, as shown and described.

DESCRIPTION

FIG. 1 is a front and right-side perspective view of the toothbrush design, showing the top cover in the open position and the bottom cover in the closed position.

FIG. 2 is a right-side view of the toothbrush thereof;

FIG. 3 is a left-side view of the toothbrush thereof;

FIG. 4 is a front view of the toothbrush thereof;

FIG. 5 is a rear view of the toothbrush thereof;

FIG. 6 is a top view of the toothbrush thereof;

FIG. 7 is a bottom view of the toothbrush thereof;

FIG. 8 is a front and right-side perspective view of the toothbrush, showing the top cover in the closed position and the bottom cover in the closed position.

FIG. 9 is a front view of the toothbrush thereof;

FIG. 10 is a rear view of the toothbrush thereof;

FIG. 11 is a left-side view of the toothbrush thereof;

FIG. 12 is a right-side view of the toothbrush thereof;

FIG. 13 is a top view of the toothbrush thereof;

FIG. 14 is a bottom view of the toothbrush thereof;

FIG. 15 is a bottom view of the toothbrush, showing the top cover in the closed position and the bottom cover in the open position.

FIG. 16 is a front and right-side exploded view of the toothbrush, showing the top cover in the open position and the bottom cover in the closed position.

FIG. 17 is a right-side exploded view of the toothbrush thereof;

FIG. 18 is a left-side exploded view of the toothbrush thereof;

FIG. 19 is a front exploded view of the toothbrush thereof;

FIG. 20 is a rear exploded view of the toothbrush thereof;

FIG. 21 is a top exploded view of the toothbrush thereof; and,

FIG. 22 is a bottom exploded view of the toothbrush thereof. The broken lines show elements of the toothbrush that form no part of the claimed design.

1 Claim, 17 Drawing Sheets
